UNITED STATES PATENT OFFICE.

HERMAN C. HEATON, OF BERWYN, ILLINOIS, ASSIGNOR TO THE BABCOCK & WILCOX COMPANY, OF BAYONNE, NEW JERSEY, A CORPORATION OF NEW JERSEY.

STEAM-BOILER FURNACE AND METHOD OF OPERATING THE SAME.

1,401,253.

Specification of Letters Patent.

Patented Dec. 27, 1921.

Application filed May 24, 1917. Serial No. 170,611.

To all whom it may concern:

Be it known that I, HERMAN C. HEATON, a citizen of the United States, residing at Berwyn, in the county of Cook, State of Illinois, have invented certain new and useful Improvements in Steam-Boiler Furnaces and Methods of Operating the Same, of which the following is a specification.

My invention relates to a furnace arrangement for steam boilers and method of operating the same in which provision is made for conveying unconsumed fuel and ash from an underfeed stoker toward the rear of the furnace chamber and there discharging the residue into a hopper. The present application is a continuation in part of my application Serial No. 16,538, filed March 24, 1915, for steam generators, Patent No. 1,242,438 issued Oct. 9, 1917.

20 In the accompanying drawings Figure 1 is a side elevation of one type of boiler containing the present improvement, certain parts being broken away and others in section; Fig. 2, a transverse section on the plane of the line 2-2 of Fig. 1; and Fig. 3, a view similar to Fig. 1, showing a modified form of conveyer with another type of boiler. Similar reference numerals indicate similar parts of the several views.

30 Referring to Fig. 1, the numeral 1 indicates a bank of horizontally inclined generating tubes connected to front and rear headers 2 and 3. These headers are connected by tubes to steam and water drums 4. Within the bank of tubes are longitudinal baffles 5 arranged as shown in Fig. 2 to direct the furnace gases across the tubes, in the space above the tubes and thence to the stack 6. In the triangular space between the bank of tubes and the steam and water drums is an economizer 7, a feed pipe 8 leads from the economizer to the steam and water drums.

40 For the purpose of illustrating my invention, I have shown, more or less diagrammatically, a Taylor underfeed stoker, although any other type of underfeed stoker may be employed. As shown, this comprises a series of retorts 9, all of which are connected to a hopper or hoppers 10. In each retort is a reciprocating plunger which pushes the fuel into the furnace. Between

the retorts are air boxes 11 from which air is delivered under pressure into the fuel pit through tuyers 12. In Fig. 1, the front 55 furnace wall 13 is shown as racked over inwardly. Below the underfeed stoker and in position to receive the unconsumed fuel and ash therefrom is an endless conveyer 14, the construction of which may be similar to 60 that of a chain grate stoker. It comprises a frame supported on wheels 15 adapted to travel on a trackway and to be moved into and out of the furnace. The conveyer 14 may be of any well-known construction 65 in which the grate surface is caused to travel around sprocket wheels 16 one of which is driven either intermittently or continuously by suitable means and the conveyer is preferably of such length as to extend from near the lower end of the underfeed stoker to the rear of the combustion chamber. The unconsumed fuel and ash from the underfeed stoker are delivered to the conveyer 14 or chain grate stoker which latter 75 is periodically or continuously advanced in order to feed toward the rear the material received by it and to discharge the residue at the rear. During the travel of the chain grate, combustible elements in the partly 80 consumed fuel will be burned, the gases passing upward and mingling with those from the fuel on the underfeed stoker. At the rear of the combustion chamber is a bridge wall 17 protected by a water box 85 18, the discharge material falling over the rear of the grate and being discharged into a hopper 19.

The chain grate stoker 14 may be withdrawn from the furnace chamber, when desired, into a passageway below the furnace floor. This passageway may be normally closed by a hinged door 20.

In Fig. 3, I have shown the standard type of B & W boiler, comprising a bank 95 of inclined generating tubes 21 expanded into front and rear headers, which latter are connected, as usual, to a steam and water drum 22. In the modification here shown, the grate 23 is materially shorter 100 than that shown in Fig. 1, and no provision is made for moving it from the furnace chamber. In this form the grate is supported on sprocket wheels 24, one of

which is driven by suitable means and, as in Fig. 1, the ash and fuel refuse are delivered from the lower end of the underfeed stoker to the traveling grate and by the latter the residue is carried to the rear of the furnace chamber and discharged into a hopper 25. A bridge wall 26 at the rear of the combustion chamber projects over the rear of the chain grate. This wall is protected 10 by a water box 27 connected with the boiler circulation through the pipes 28 and 29.

As is well-known, the fuel supporting surface of the underfeed stoker illustrated in the drawings is inclined, and the fuel and 15 ash are gradually moved to the lower end thereof. From this point they are discharged upon the horizontal surface of the traveling grate by which they are conveyed through the furnace. As they are so conveyed 20 any unconsumed combustible elements in the fuel will be burned, thereby effecting an economy in the operation of furnaces fired by an underfeed stoker. The arrangement described does away with the 25 use of dumping plates, clinker grinders and other similar devices as heretofore generally used with underfeed stokers.

The underfeed stoker combined with the chain grate stoker gives better results and 30 higher efficiencies than would be secured through the use of other types of stokers combined with the chain grate stoker.

An underfeed stoker is supplied with a forced blast, and the amount of coal burned 35 on the underfeed stoker can be regulated independently of the suction within the furnace chamber. The suction within the furnace chamber can, therefore, be made such as is best adapted for burning the coal on 40 the chain grate stoker, and both the chain grate stoker and the underfeed stoker can be operated at their maximum efficiencies. Should any other stoker than the underfeed 45 be used where a forced draft is not available, and the coal from the other type of stoker fed to the chain grate stoker, the amount of furnace draft required for the other type of stoker would be considerably more than that required for burning the 50 partly spent coal on the chain grate stoker, and the result would be that a great amount of excess air would pass into the furnace through the coal on the chain grate stoker and uneconomical results would be secured. 55 The combination disclosed in the application is, therefore, one that can be operated at higher efficiencies than would be obtained with other forms of stokers combined with the chain grate.

60 What I claim and desire to secure by Letters Patent of the United States is:—

1. A fuel burning method comprising 65 forcibly underfeeding fuel into the front portion of bed of burning fuel and there-
beyond bodily carrying along the fuel bed

rearward with substantially horizontal travel toward the discharge.

2. A method according to claim 1, and wherein the operations proceed with substantial continuity and at such speed of 70 travel of the fuel bed that the combustion continues substantially to the discharge.

3. A fuel burning furnace, including in combination, means for forcibly underfeeding fuel rearwardly into the front portion 75 of the bed of burning fuel, and to the rear thereof of a traveling endless grate adapted to bodily carry along the fuel bed rearward in a substantially horizontal direction toward the discharge. 80

4. A steam boiler furnace having an underfeed stoker and a forced air blast, and a traveling chain grate at the rear of the stoker, the stoker being arranged to feed fuel and ash upon the traveling chain grate. 85

5. In a boiler furnace the combination with an underfeed stoker having a forced air blast, of a movable grate upon which the fuel and ash are discharged, said grate being arranged to convey the residue to the 90 rear of the furnace, a bridge wall at the rear of said chamber, and a water-box for protecting said wall, the discharge of the ashes being through the space between the grate and the said water-box. 95

6. A steam boiler furnace having an underfeed stoker and a forced air blast, an endless refuse removing device at the rear of the stoker, and connections for continuously actuating said endless refuse removing device 100 to discharge the residues fed thereto by the stoker.

7. A steam boiler furnace having a combustion chamber, an underfeed stoker disposed at the front of said combustion chamber, and a traveling chain grate disposed at the rear of said chamber and constructed and arranged to receive fuel and ash from the underfeed stoker in one portion thereof and discharge the refuse from another portion thereof. 105

8. A steam boiler furnace having an underfeed stoker and a forced air blast, and a traveling chain grate at the rear of the stoker, the stoker being arranged to feed fuel 110 and ash upon the traveling chain grate, said chain grate having an air supply separate from that of said underfeed stoker.

9. In a boiler furnace, the combination with an underfeed stoker having a forced air blast, of a movable grate upon which the fuel and ash from said stoker are discharged, said grate being arranged to convey the residue to the rear of said furnace and having an air supply separate from that of said 120 underfeed stoker.

10. In a boiler furnace, the combination with an underfeed stoker having an inclined bed and a forced air blast, of a movable 125 grate extending rearwardly from said 130

stoker and having a substantially horizontal surface upon which the fuel and ash from said stoker are discharged, said grate being arranged to convey the residue to the rear of the furnace, and having an air supply separate from that of said underfeed stoker.

In testimony whereof I have hereunto

signed my name in the presence of two subscribing witnesses.

HERMAN C. HEATON.
